UNITED STATES PATENT OFFICE

HENRY W. ADAMS, OF CINCINNATI, OHIO

VOICE TRANSMITTER

Application filed March 21, 1931. Serial No. 524,285.

This invention relates to a non-electrical voice-transmitting means, embodied in the present instance, in a toy telephone, though other embodiments thereof, such as in inter-office communicating means, and the like, are obvious.

An object of the invention is to provide a device of the class described for communication over comparatively short distances.

Another object is to provide such means which may be incorporated in a device of conventional appearance and of convenient construction for movement and manipulation by a user, and adapted to be placed on a desk, table or the like.

Another object is to produce such a device having separate and independently movable mouth and ear pieces.

Another object is to provide such means adapted for simple and efficient construction.

These and other objects are attained by the means described herein and set forth in the accompanying drawing, in which:

Fig. 1 is a side elevational view, partly in cross section, of a toy telephone embodying the means of this invention.

Fig. 2 is a fragmentary cross-sectional view similar to Fig. 1 and showing modified means of the invention.

Fig. 3 is a cross-sectional view taken on line 3—3 of Fig. 2.

The telephone illustrated in Fig. 1 comprises a base 5, stem 6, neck 7, and mouthpiece 8, which together constitute the "phone" body, two or more of the complete telephones connected by flexible tubing constituting a portable "phone" system. Stem 6 may be threadedly mounted in base 5, as indicated at 9, and is provided throughout its length with the central aperture 10, the neck 7 providing a continuation of this passageway into the mouthpiece 8.

A chamber 11, is formed in base 5, said chamber communicating at its inner end with passageway 10 of the positioned stem 6, and opening at its outer end upon the lateral surface of base 5. This lateral opening, and the entire upper surface of base 5, is provided

50 with a covering 12, of sheet metal or the like.

Chamber 11 constitutes a sound chamber. A flexible tube 13, preferably of rubber communicates at one end 14 with this chamber, and at the other end, with a longitudinally-apertured receiver 15, normally suspended at 55 the side of stem 6 upon a hook 16. An extended flexible tube 17 likewise communicates, at one end 18, with chamber 11, and at the other end, with the similar chamber of a second toy telephone, identical in all respects, with the one herewith described.

A bell 19, of the "bicycle" type, may be positioned at one side of the toy telephone.

The person speaking into mouthpiece 8, transmits voice through passageway 10 and chamber 11 and tube 17 into the like chamber of the communicating telephone. Here the voice may be readily heard by another person holding the receiver 15 to his ear, such person responding, of course, through the 70 mouthpiece on his telephone.

A modified form is illustrated in Figs. 2 and 3. Herein, the upper portion of the base 20 is provided with the eccentric aperture or chamber 21 opening on the surface of the base and extending into but not through the base. A bore 22 extends from the bottom 23 of aperture 21 through the base 20, said bore being disposed centrally of base 20 for receiving and having suitably secured therein 75 the hollow stem 24. A transverse bore or aperture 25 in stem 24 effects communication between the hollow interior of the stem and the chamber 21. The whole upper face of base 20, and chamber 21 are provided with 80 the cover 26, the tubes 17 and 13 being placed in communication with the chamber 21 thus 85 enclosed. A plug 27 closes the bottom of hollow stem 24. This modification is adapted for great simplicity in manufacture.

A device of the kind described is practicable when used with lengths of communicating tubing 17 up to approximately 50 feet, there being no need, for exerting the voice above normal. Within such circumstances, the device of this invention provides an efficient and cheaply installed voice transmitting means.

What is claimed is:

1. In a portable voice transmitting and re-

100

ceiving means, the combination of a telephone body having a chamber therein, an ear and a mouth appliance, relatively independent and movable, and each communicating with said chamber, and a tube communicating at one end with said chamber and at the other end with the chamber of a second and similar voice transmitting means.

2. Voice transmitting and receiving means

10 comprising a base member having a closed chamber therein, a hollowed stem attached to the base, communicating with the chamber and having a communicating mouthpiece at the outer end thereof, an independent longitudinally-apertured receiver communicating with said chamber by means of a flexible tube, and an extended tube communicating at one end with said chamber and at the other end with the like chamber of similar 20 voice transmitting means.

3. Voice transmitting and receiving means comprising a base member having a chamber therein opening at one end upon the upper central portion of said base and at the other 25 end upon a lateral portion of the base, a hollow stem having a mouthpiece at its upper end and at its lower end attached centrally of said base in communication with said chamber, a member embracing said stem and covering the base including the lateral opening of said chamber, a hollow receiver member and a pair of tubes attached to said covering and communicating at one end with said chamber at the lateral opening thereof, 35 one of the tubes communicating at its opposite end with the hollow interior of said receiver member and the second tube communicating at its opposite end with the chamber of similar voice transmitting and receiving 40 means.

4. Voice transmitting and receiving means comprising a base member having an open chamber in its upper surface and a bore extending from the bottom of said chamber 45 through said base, a hollow stem positioned in said bore and provided adjacent its lower end with an aperture effecting communication between said chamber and the hollow interior of said stem, a hollow receiver member, a member embracing the stem and covering said base including said chamber, and a pair of tubes, one end of each tube communicating through said chamber with the hollow interior of the stem, the opposite ends of the tubes communicating, one with the hollow interior of said receiver member the other with the chamber of similar voice transmitting and receiving means.

5. A portable voice transmitting and receiving means comprising a body having an enclosed chamber therein, an ear and a mouth appliance, each communicating with said chamber, and a flexible tube communicating at one end with said chamber and at

the other end with the chamber of a second and similar voice transmitting means.

6. In a portable toy telephone system the combination of a plurality of telephone bodies each comprising a receiving member and a transmitting member, hollow means providing communication between said receiving and transmitting members and hollow flexible means connecting with said telephone bodies and providing back and forth 75 voice transmission between all of said transmitting and receiving members.

In testimony whereof, I have hereunto subscribed my name this 17th day of March, 1931.

HENRY W. ADAMS.
